ASH TRAY

Joan W. Blutter, 2801 N. Sheridan Road,
Chicago, Ill. 60657

Filed Aug. 6, 1973, Ser. No. 385,688

Term of patent 14 years

Int. Cl. D27—03

U.S. CL. D27—14

FIG. 1 is a perspective view of an ash tray showing my new design;

FIG. 2 is an end elevational view thereof, on a reduced scale, as seen from the line 2—2 of FIG. 1;

FIG. 3 is a front elevational view thereof, on a reduced scale;

FIG. 4 is a top plan view thereof, on a reduced scale;

FIG. 5 is a rear elevational view thereof, on a reduced scale;

FIG. 6 is a sectional view thereof, on a reduced scale, taken on the line 6—6 of FIG. 5;

FIG. 7 is a bottom plan view thereof, on a reduced scale;

FIG. 8 is a top plan view of an ash tray showing a modified form of my new design, the modification residing in the support bracket; and

FIG. 9 is a rear elevational view thereof.

I claim:

The ornamental design for an ash tray, substantially as shown and described.
